LISTING ADDING MACHINE

Loring Pickering Crosman, Maplewood, N. J., assignor to Gardner Company, Orange, N. J., a corporation of Delaware

Application December 14, 1936, Serial No. 115,853

4 Claims. (Cl. 235—60)

The invention relates to listing registers, namely those adding and subtracting machines operating to print or list the items, and more particularly to such registers provided with a key-board having digital keys common to the accumulator and printing mechanisms.

It is necessary when printing totals of accumulative values from such registers to render the keyboard mechanism inoperative, this being usually done by clearing the keyboard of any values set therein and locking the keys against depression in well known manner. This however renders the keyboard inoperative until near the end of a cycle of operation, and it is an object of the present invention to provide means controlled by the total-taking mechanism for rendering the keyboard operative during a totaling or a sub-totaling cycle. Another object is to provide similarly controlled means to accomplish said object and also to render the keyboard clearout means inoperative during such cycle. Another object is to provide similarly controlled means for accomplishing said object and also for rendering inoperative the means for preventing operation of the digital keys during such cycle.

The invention consists in the novel construction and combinations of parts as hereinafter set forth in the claims.

In the accompanying drawings,

Figure 1 is a vertical section taken through the registering and printing mechanisms of the machine to which the invention is shown as applied.

Figure 2 is a right side elevation of the total and sub-total control mechanisms.

Figure 3 is a right side elevation of parts of the machine controlled by the totaling mechanism for disengaging the actuating mechanism from the keyboard.

Figure 4 is a front elevation of the same with the keyboard held in horizontal position.

Figure 5 is a detail plan view, showing the differential elements or stop bars of the actuating mechanism moved to disengaged position relative to the stems of the digital keys.

Figure 6 is a left hand elevation of the keyboard locking mechanism.

General operation

For each denominational order, the machine is provided with a three-armed actuator lever designated 610 (Fig. 1), these levers being loosely mounted on a shaft 608. The forward arm of each lever 610 terminates in a segmental registering rack, the rearward arm has a lister type bar 611 pivoted thereto, and the upper arm has

a pivotal connection with a differentially movable toothed member or stop bar 615, cooperating with a column of digital keys 215 for each said order the teeth of said member being variably spaced.

The digital keys 215 which have been depressed to represent a value, are latched in depressed position by slide plates 216, with the lower ends of the key stems lying in the paths of movement of the related teeth of said members or bars 615, thereby allowing said bars to advance a distance corresponding to the values of said keys, upon operation of the machine. Depression of a digital key will also remove a column latch 214 from the path of movement of its related bar 615, these latches preventing movement of a stop bar 615 and a lever 610 in any column in which no digital key is depressed.

A rock shaft 301 is provided with cam means 318 for governing the movement of a spring tensioned rocker frame 616, mounted on shaft 608, said frame 616 carrying a series of dogs 617 normally engaged by studs 659 of the levers 610. As shaft 301 is rotated forwardly, the frame 616 will be rocked, and any of the levers 610 which have been released by the depression of digital keys will be allowed to rotate, under the influence of their springs 683, until they are stopped by the related teeth of the bars 615 contacting the stems of said keys. Upon rearward rotation of shaft 301, the dogs 617 will return the operated levers 610 to normal position.

This excursion of the levers 610 serves to register amounts set in the keyboard upon one or more accumulators and to set up a similar amount on the printing line of the type bars.

These accumulators are shown in Patent No. 1,867,002, as means for storing positive or negative totals, to be printed. Tens carry mechanism is provided in accord with the disclosure of Patent No. 1,828,180.

Motor drive means

The shaft 301 is oscillated by means of an electric motor 100, connected through gearing 101 (Fig. 2) and clutch means with a crank arm 105, of a shaft 105', one of the gears 101 having an extended hub provided with a notched periphery 3', forming one member of said clutch, and the crank arm 105 having pivoted thereto a pawl 103, adapted to engage one of the notches of said hub and forming the other member of said clutch, a spring 2' connecting one arm of said pawl with said crank arm tending to move said pawl into engagement with a notch of said hub to thereby

render the clutch operative. Clutch lever 106 is fulcrumed at 107 to the framing of the machine and normally engages the lower arm of said pawl to hold the latter disengaged from said clutch hub. The crank arm 105 is connected to an arm 316 fast with shaft 301 by means of a connecting rod 108, so that as crank arm 105 is rotated, the shaft 301 is oscillated.

To establish the drive, clutch lever 106 being 10 rocked about its fulcrum, the contact members of a switch in circuit with said motor are engaged, all as disclosed in one of said patents, to thereby start the motor. At the same time, the lower arm of the clutch lever 106 will be disengaged from the clutch pawl 102, whereupon said pawl will engage said clutch hub of the crank arm 105, to render said clutch operative.

The spring 111 tends to disengage clutch lever 106 from said pawl, said lever being normally 20 held in engaging position by means of a latch 112, the latter being released upon depression of a general operation key as described in one of said patents. This latch will return under spring action to latching position, and towards the end of 25 the cycle of operation an arm 115 of crank member 105 will contact a tooth 116 of clutch lever 106 and thereby force said lever back to latching position and bring the end of said lever into the path of movement of the clutch pawl 103 to 30 release the same from the clutch hub.

Keyboard clearout

During a cycle of operation, a lever 327 fast 35 on shaft 302 and having a link connection 324 with said arm 316 is oscillated to thereby release the digital keys 215 and clear the keyboard near the end of the cycle by means as follows:

Upon the forward stroke of the parts carried by shaft 301, an arm of lever 327 will be carried 40 above the roller of click pawl 222 pivotally mounted on rock plate 220, and during a return stroke of these parts said lever will rock said plate clockwise about its pivot 218 and a pawl 219 pivotally 45 secured to said plate will engage a stud 263 secured to clearout bail 221 to thereby operate the column latches 214 and move slides 216 forwardly and release any depressed digital keys 215.

Operation preventing means for the digital keys

50 The following means are provided to prevent operation of the keys 215 during a regular cycle of operation:

Upon the forward stroke of the parts stated, an 55 arm 226 (Fig. 3) fast to the shaft 301 will be carried away from a pin 228 of slide 230, thereby releasing the slide.

Secured to the left hand end of the shaft 224 60 is a depending finger 231 (Fig. 6) urged by means of its spring 232 against a pin 233 secured to the aforesaid slide 230, which being released as stated, the finger 231 will be rocked by its spring to rock shaft 224, and thereby bring the latch pawls 225 carried by shaft 224 into engagement with projections 234 of the slides 216 and lock said slides 65 against forward movement to thus prevent depression of the digital keys 215.

Near the end of the cycle, the arm 226 will 70 re-engage the pin 228 of slide 230 and move said slide rearwardly to thereby lift the latch pawls 225 from engagement with the slides 216 and unlock the keyboard.

Total printing

75 A total is taken by releasing the differentially

movable elements or stop bars 615, the latter being then spring actuated to rotate the accumulators subtractively until suitable pins on the accumulator wheels contact with 0 stop members as hereinafter described. This will set up the total 5 in the type bars, and the hammers will be tripped to print the total. The bars 615 are then re-engaged with the oscillatory frame 616 and during the return stroke of the latter said bars are moved rearwardly to normal position, the accumulator wheels, in the case of a sub-total, being held in engagement with segmental racks of the actuator levers during the return stroke of the parts, whereby the amount previously subtracted from the register will be added back thereinto in 15 well known manner.

Depression of the total key 278 or the sub-total key 273 will not only trip the column latches 214 (Fig. 1) through the pin 263 and the clearout bail 227, but will also trip a latch 620 (Fig. 2) 20 through operation of a control lever 621, pivotally connected to said latch. The latch 620 normally engages a lug of total segment 618, preventing movement of said segment under the influence of its spring 681. Upon the tripping of said latch 25 620, total segment 618 will operate a shaft 607, having a helically arranged row of pins, acting to trip the latching dogs 617 successively from right to left of the machine, the tripping of said dogs releasing the actuator levers 610 and also 30 releasing stop members 613, so that the latter will fall into the path of the 0 stops 457 of the accumulator wheels.

When this zeroizing operation has progressed to the left hand side of the machine, a rearwardly extending arm of the total segment 618 will 35 contact a projection of rod 130 having connection with trigger 131, to move said rod downwardly, thereby releasing the latch 112 to start the machine in operation. The machine being thus 40 started, the frame 616 will carry the dogs 617 forwardly and said dogs will snap under the stop members 613 and the studs 659 of the actuator levers. The hammers will now be tripped, and upon rearward movement of the frame 616, the 45 actuator levers will be restored to normal position.

The total and the sub-total keys are each locked in depressed position by latch 223, and released 50 near the end of the cycle of motor operation by engagement of an arm of the lever 327 above click pawl 222 of latch striker plate 220, the parts of the total setting mechanism being then restored to normal position by means described as 55 follows:

In tripping the total segment latch 620 (Fig. 2), the shaft 206 is rocked by engagement of key 278 or 273 with crank arm 239 of said shaft, an arm 229 of said shaft being then operated by spring 15 connecting arms 239 and 229 and contacting with a pin 132 of the latch control lever 621 to trip said latch. The latch being tripped and total segment 618 rising under influence of its spring, the latching lug 618' of said segment will contact said lever 621 to thereby move said 65 pin 132 out of contact with arm 229 and into contact with a shoulder 133 of one arm of a rock lever 134 on shaft 134', pin 132 being held against said shoulder by the action of the spring 621'. During the following motor operation of 70 the machine, the forward movement of cam 318 on shaft 301 will release a spring tensioned push rod 135 connected to the other arm of said rock lever at 135' to thereby move shoulder 133 until said pin 132 comes below arm 229, and upon re- 75

lease of the total or the sub-total key the latch 620 and the arm 229 will be restored to normal position by the action of the latch spring, thus concluding the totalizing operation.

- 5 The type bars 611 are provided each with a row of type representing the digits 1 to 9 and 0, the 0 or zero type being normally on the printing line. When the actuator levers 610 are moved in accord with a key setting or an accumulator 10 registration, the related type bars will be raised to bring the appropriate type to the printing line. The type hammers 715 (Fig. 1) are adapted to be operated by spring actuators 700, but are normally held in tensioned position by latches 701. 15 When a type bar is raised, a tripping finger 702 is allowed to move into engagement with the corresponding latch 701, and at the end of the forward movement of shaft 301, a frame upon which the tripping fingers are mounted is moved forwardly, thereby releasing the hammers from those latches which have been engaged by the fingers 702.

Free keyboard mechanism

- 25 To provide for operativeness of the digital keys 215 while a total or a sub-total cycle is in progress, the forward and rearward supports 1 and 2 of stop bars 615 are slidably mounted in the machine frames 3 and 4 (Figs. 1 and 4). Upon depression of a total or a sub-total key, means are provided as follows to move the stop bars 615 towards the right and out of cooperative relation with the stems of the digital keys 215.

Pivotedly mounted at 5 (Fig. 3) to the framing 35 of the machine is a cam plate 6 provided with projections 7 and 8 underlying the total and the sub-total keys 278 and 273. The lower cam surface 6' of the plate 6 is in engagement with an arm 9 (Fig. 4) of a bail lever 10, pivotally mounted upon supports 11 and 12 fast to the framing 40 of the machine. The bail lever 10 has pin and slot engagement 13 with the supports 1 and 2 of the stop bars 615, and upon depression of a total or a sub-total key 278 or 273, the plate 6 will 45 cam said bail lever 10 clockwise as seen in Figure 4, thereby sliding the supports 1 and 2 towards the right and carrying the said stop bars 615 out of register with the stems of the digital keys 215, as seen in Figure 5.

50 The total and the sub-total keys 278 and 273 are each adapted to be held in depressed position by means of a latch 223, tensioned by the aforesaid spring 15. Near the end of the cycle of operation, the arm 327 will rock the plate 220 in 55 the manner previously described, and a tooth of said plate will contact pin 217 (Figure 2) of the latch 223, thereby releasing the depressed key; and bail lever 10 being restored to normal position by action of the spring 16 will again bring 60 the stop bars 615 into register with the stems of the digital keys 215.

The following means are provided to render 65 the keyboard clearout mechanism previously described.

65 The rocking of the arm or bell lever 229 during depression of the total or the sub-total key will cause a rearwardly extending arm 229' of said bell lever to engage lug 17 of latch 223, thereby 70 rocking said latch clockwise (Figs. 2 and 3). Lug 70 17 underlies one arm of a bell lever 18, pivotally mounted at 19 and will rock the same in a clockwise direction. The upper arm of said bell lever 18 has engagement with a slide 20 provided with a projection 21 having engagement with one arm 75 of the pawl 219. Clockwise movement of bell

lever 18 will therefore move slide 20 rearwardly, thereby rotating the pawl 219 about its pivot sufficiently to bring the hook end of said pawl out of cooperative relation with the stud 263 of the clearout bail 227, and as the arm 327 rocks 5 the plate 220 in the manner previously described, the pawl 219 will move idly past stud 263, the keyboard clearing devices being thus rendered inoperative until release of the depressed key 278 or 273. 10

The keyboard locking devices will also be rendered inoperative during a total or a sub-total cycle by means described as follows:

Secured to the left hand end of the slidable support rod 1 of stop bars 615 is a bracket 22 15 (Figures 4 and 6) provided with an arm 23 adapted, as rod 1 is moved towards the right in totals taking, to be moved into the path of movement of a pin 24 secured to the aforesaid slide 230. This will prevent the forward movement of 20 said slide 230 during a cyclic movement of the machine, thereby holding the depending finger 231 in rearward position, the locking pawls 225 thus being held upwardly out of engagement with the slide 216. 25

I claim:

1. In a listing register, comprising an accumulator, printing mechanism, a keyboard having digital keys, means for holding said digital keys in set position, actuating means for said accumulator and said printing mechanism, differentially movable elements cooperating with said digital keys and said actuating means, total-taking means, said actuating means operating under control of said total-taking means to set up a total from said accumulator in said printing mechanism, to print said total, to reset the accumulator and to restore parts to normal position, and cyclically operable means for releasing the holding means to clear the keyboard; means controlled by said total-taking means for moving said differential elements out of register with said digital keys and for rendering the keyboard clearout means inoperative during a totaling cycle. 35

2. In a listing register, comprising an accumulator, printing mechanism, a keyboard having digital keys, means for holding said digital keys in set position, actuating means for said accumulator and said printing mechanism, differentially movable elements cooperating with said digital keys and said actuating means, total-taking means, said actuating means operating under control of said total-taking means to set up a total from said accumulator in said printing 40 mechanism, to print said total, to reset the accumulator and to restore parts to normal position, and cyclically operable means including a clearout member and a device engaging the same 45 for releasing the holding means to clear the keyboard; means controlled by said total-taking means for moving said differential elements out of register with said digital keys and for holding said device disengaged from said clearout member during a totaling cycle. 50

3. In a listing register, comprising an accumulator, printing mechanism, a keyboard having digital keys, means for holding said digital keys in set position, actuating means for said accumulator and said printing mechanism, differentially movable elements cooperating with said digital keys and said actuating means, total-taking means, said actuating means operating under control of said total-taking means to set up a total from said accumulator in said printing 55 mechanism, to print said total, to reset the accumulator and to restore parts to normal position, and cyclically operable means including a clearout member and a device engaging the same 60 for releasing the holding means to clear the keyboard; means controlled by said total-taking means for moving said differential elements out of register with said digital keys and for holding said device disengaged from said clearout member during a totaling cycle. 65

4. In a listing register, comprising an accumulator, printing mechanism, a keyboard having digital keys, means for holding said digital keys in set position, actuating means for said accumulator and said printing mechanism, differentially movable elements cooperating with said digital keys and said actuating means, total-taking means, said actuating means operating under control of said total-taking means to set up a total from said accumulator in said printing 70 mechanism, to print said total, to reset the accumulator and to restore parts to normal position, and cyclically operable means including a clearout member and a device engaging the same 75 for releasing the holding means to clear the keyboard; means controlled by said total-taking means for moving said differential elements out of register with said digital keys and for holding said device disengaged from said clearout member during a totaling cycle. 80

mechanism, to print said total, to reset the accumulator and to restore parts to normal position, and cyclically operable means cooperating with said holding means to prevent operation of 5 said digital keys after initiation of a cycle of operation; means controlled by said total-taking means for moving said differential elements out of register with said digital keys and for rendering said key operation preventing means inoperative 10 during a totaling cycle.

4. In a lasting register, comprising an accumulator, printing mechanism, a keyboard having digital keys, means for holding said digital keys in set position, actuating means for said accumulator and said printing mechanism differentially movable elements cooperating with said digital keys and said actuating means, total-taking means, said actuating means operating under 15

control of said total-taking means to set up a total from said accumulator in said printing mechanism, to print said total, to reset the accumulator and to restore parts to normal position, and cyclically operable means cooperating 5 with said holding means to prevent operation of said digital keys after initiation of a cycle of operation including a longitudinal slide device; means controlled by said total-taking means for moving said differential elements out of register 10 with said digital keys and for rendering said key operation preventing means inoperative during a totaling cycle including a transverse slide device engaging said differential elements, and means carried by said transverse slide device and 15 engaging said longitudinal slide device.

LORING PICKERING CROSMAN.
